BINDING COVER AND ENVELOPE
CONSTRUCTION

Glenn Swift, Darlington, Wis.

Application October 6, 1939, Serial No. 298,310

14 Claims. (Cl. 129—1)

This invention relates to improvements in binding cover and envelope construction, and in its more specific aspects to a binder functioning to secure a plurality of sheets in assembled relation on a cover, combined with an envelope which may contain correspondence or other data related to the subject-matter of the bound sheets.

The proposal of the present invention, while not limited thereto, was designed for and has particular application as a binder for title abstracts and like manuscripts, in the assembly of which it was heretofore customary to fasten the plat into the abstract or else merely insert the plat between the sheets of the abstract. When fastened into the abstract, the tendency existed to reduce the plat to the usual legal size of the abstract pages and this reduction often resulted in a drawing scaled too small for convenient working. Fastening of the plat into the abstract further resulted in inconvenience to one working with the papers in question as it compelled repeated reference back to the fastened plat for checking descriptions and like operations.

Where the plat was merely inserted between the sheets it was easily lost during handling or filing of the abstract.

Accordingly in the construction of an effective abstract cover recognition must be given to the fact that the plat should be separate and detached from the pages of the abstract so that the drawing can be shown in convenient scale and so that it can be handled freely and placed alongside the abstract when working therewith. At the same time provision must be made for protection against loss of the plat and related papers containing pertinent data to the abstracted title, for their retention with the abstract during periods of filing, and for rendering the plat and related data readily accessible for use.

Accordingly an object of the present invention is the provision of a combined binder and envelope of improved construction which provides binding means and a cover for the sheets to be bound and also providing a readily accessible receptacle or envelope for containing plats, drawings, correspondence and other data pertinent to the subject-matter of the bound sheets. A further object is the provision of a combined binder and envelope construction which may be inexpensively manufactured, which is durable in use, and by which sheets may be bound in simple manner and data and correspondence pertinent thereto may be retained therewith during filing and other periods in such manner that all

of the related material is suitably protected and at the same time readily accessible for use. A further object is the provision of a binding cover for sheets to be bound, which is so constructed and arranged as to give adequate protection to the bound sheets, to improve their appearance, and to protect the bound sheets from falling away from the cover when the binder is filed on edge.

Other objects will be in part obvious and in part hereinafter pointed out in connection with the following analysis of this invention wherein is illustrated an embodiment of the invention in detail.

In the drawings—

Fig. 1 is a plan view of one form of binding cover and envelope construction of the present invention;

Fig. 2 is a section taken along line 2—2 of Fig. 1;

Fig. 3 is illustrative of an alternative arrangement of the binding flaps;

Fig. 4 is a face view of the blank from which the binder and envelope of Figs. 1—3 is formed;

Fig. 5 is a part face view of a blank for a combined binder and envelope as aforesaid employing a modified form of binding flap;

Fig. 6 is a section taken through the binding flap constructed from a blank such as shown in Fig. 5;

Fig. 7 is a face view of a blank for forming another embodiment of combined binder and envelope in accordance with the present invention;

Fig. 8 is a section taken through a binder and envelope construction formed from the blank illustrated in Fig. 7;

Fig. 9 is a section along line 9—9 of Fig. 8;

Fig. 10 is a part face view of a blank for forming a binder and envelope construction employing the binding flap arrangement as illustrated in Figs. 7 and 8 but utilizing a modified form of pocket for receiving the lower ends of the bound sheets;

Fig. 11 is a plan view of a binder and envelope fabricated from a blank such as illustrated in Fig. 10;

Fig. 12 is a part transverse section of the binder and envelope illustrated in Fig. 11, being taken along line 12—12.

Referring now to the drawings wherein like reference characters designate like parts throughout the several views, the combined binding cover and envelope of the form illustrated in Figs. 1—4 is generally designated at 10 (Fig. 1) and serves as a binding for a plurality of sheets 11 secured

to binding flaps to be described as by pronged fasteners 12, 13.

By reference to Fig. 4 which is illustrative of a blank from which the binder and envelope of Fig. 1 is formed, the blank is cut as illustrated to provide a front cover sheet 15 (defined by a left hand fold line 16, a right hand fold line 17, a top fold line 18, and a bottom fold line 20), and a back sheet 21 (defined by right hand marginal edge 22, the fold line 17, a top fold line 23, and a bottom marginal edge 24). As fold line 23 is in effect a continuation of fold line 18 and as the bottom marginal edge 24 is a continuation of fold line 20, it will be understood that the length of the front and back sheets 15, 21 is the same, being somewhat greater than the length of the bound sheets 11. The width of said sheets 15, 21 is substantially the same, being somewhat greater than the width of the bound sheets 11, so that when front sheet 15 is folded forwardly about line of fold 17 to overlie back sheet 21, the marginal edge 22 underlies the line of fold 16.

Extending relatively upwardly of the front sheet 15 is a binding flap 25 and extending upwardly of the back sheet 21 is a related binding flap 26, said flaps being adapted for folding in relatively forward direction along lines of fold 18, 23. The depth of the flaps 25, 26 is in the form under description substantially the same, being sufficient to provide suitable anchorage for the fasteners 12, 13. The width of the flaps is substantially the width of the cover sheets from which they extend and hence is somewhat in excess of the width of the bound sheets 11.

Extending downwardly of the front sheet 15 and adapted for upward folding with reference thereto along a line of fold 20 is a bottom flap 28 of width substantially equal to that of the front sheet 15 and of substantial depth. The flap 28 for the greater portion of its depth is defined on its right hand edge by a line of fold 30 from which extends a wing flap 31.

Extending sidewardly of the front sheet 15 and adapted to be folded rearwardly thereof along the line of fold 16 is a strengthening flap 32 of substantial width and of depth substantially that of the front sheet.

Preferably the relatively under faces of the flaps 28 and 31 are coated with adhesive, preferably during manufacture of the blank, as indicated by the cross-hatching. If desired, one or both of the adjacent faces of the binding flaps 25, 26 may also be coated with adhesive whereby these flaps, which engage in the manner illustrated in Fig. 2, can be adhesively secured together.

The front sheet 15 is provided with a slit 35 which extends in a straight line substantially across the sheet and hence is of somewhat greater length than the width of the bound sheets 11. The slit 35 is spaced from the bottom edge of the binder as defined by the line of fold 20 a sufficient distance as to provide a pocket of substantial depth for the reception of the bottom end portions of the bound sheets 11. It will be here noted that the depth of wing flap 31 is somewhat less than the spacing between slit 35 and line of fold 20 so that the flap in final position will not overlap the slit 35.

In setting up the combined binding cover and envelope blank illustrated in Fig. 4, front sheet 15 is folded forwardly along the line of fold 17 and to a position overlying the back sheet. Thereupon bottom flap 28 is folded rearwardly along line of fold 20 to underlie the back sheet

21 and is glued by its adhesive coat to the back face of the back sheet 21, thus to close the bottom of the structure, the bottom edge of which is now defined by the line of fold 20.

The side wing flap 31 may now be folded relatively forwardly along line of fold 30 and is glued to the front face of the front sheet 15 which it overlies. The flap 31 serves not only to strengthen the pocket but also reinforces the binding cover along an edge which would receive wear during edge filing.

Flap 32 may now be folded inwardly along line of fold 16 to lie between the front and back sheets 15, 21, respectively. While no gluing of the flap 32 to the front sheet is contemplated, nevertheless the flap 32 provides strengthening and reinforcing properties and further acts to protect one right hand edge of the cover as defined by the line of fold 16.

Binding flaps 25, 26 may now be bent relatively forwardly along fold lines 18, 23 to a position in which they overlie front sheet 15 as indicated in Figs. 2 and 3. If the flaps are to be adhesively secured, they are glued together along their meeting faces to close the top of the structure, the top edge of which is now defined by the lines of fold 18, 23. Preferably, however, the flaps are unglued, in which case reliance for securing of the flaps is placed on the fasteners 12, 13 which extend therethrough and also through the sheets 11 to be bound, hence to secure the latter to the cover.

Upon proper assembly and relation of the sheets to be bound, the top edge of the latter may be inserted into the recess or mouth formed by the overhanging and preferably unglued flaps 25, 26, as indicated in Fig. 2. Thereupon suitable fasteners such as the pronged fasteners 12, 13 are passed through the flaps and sheets 11, the bent prong ends in this instance being covered by both the front and the back sheets of the cover. It will be understood of course that the prongs may also be passed through the said front and back cover sheets and their ends bent against the rear face of the cover back sheet.

In Fig. 3 an alternative arrangement of securing and binding the sheets to the flaps 25, 26 is illustrated. According to this alternative proposal, the flaps 25, 26 are glued together and the top portions of the sheets 11 are inserted into the gap provided between the secured flaps 25, 26 and the front cover sheet. Upon passing the fasteners 12, 13 through the glued flaps, the intermediate sheets being bound, and both cover sheets, the prongs thereof may be bent against the rear face of the back cover sheet.

The lower edge portions of the bound sheets 11 may now be inserted through the pocket mouth provided by the slit 35 and into the pocket formed along the lower edge of the cover. Such a pocket construction is beneficial not only for protecting the lower edge portions of the bound sheets but also prevents the bound sheets from falling away from the cover when the cover and sheets are filed on edge.

It will be noted that the front and back sheets according to the above described construction, while secured along their top and bottom edge and along the left side, are left unsecured along the right edge thereof. Accordingly this arrangement provides not only a binding and cover but also an open-sided envelope adapted to receive plats, correspondence, and/or data pertinent to the subject-matter of the bound sheets. It is further seen that the envelope and its opening

is readily accessible to one working with the bound sheets and at the same time provides a pocket or envelope in which additional material not susceptible to binding may be retained with the binder and thus protected against loss, misplacement and the like.

Referring now to the modified binding arrangement illustrated in Figs. 5 and 6, the blank shown in Fig. 5 is the same as illustrated in Fig. 4 with the exception of the binding flap arrangement employed in the modification currently under description. In the modified construction, the front sheet 15 is provided with a flap 25a similar to the flap 25 of the Fig. 4 blank. The back sheet 21, however, is provided with a flap of depth substantially three times the depth of the flap 25a, thus upon appropriate bending to provide flap plies 26a, 26b, 26c. In assembling a binding cover from the Fig. 5 form of blank, front cover sheet 15 is folded to overlie the back sheet 21, thus bringing flap 25a onto flap-ply 26a. Glue or like adhesive is applied to flap-ply 26b, and the latter is folded downwardly along line of fold 23a and glued to flap 25a. Flap-ply 26c is now folded upwardly along line of fold 23b. Thereupon, the entire flap structure composed of the several plies is folded forwardly along the line of fold 23. By such a ply arrangement, the flap 25a is interleaved between the plies 26a, 26b in the manner illustrated in Fig. 6.

As will be further seen in Fig. 6, there is provided a gap between the plies 26b, 26c of the back sheet carried flap, in which the top edge portions of the sheets 11 to be bound may be inserted. Thereupon pronged fasteners such as 12, 13 may be passed through the plies and sheets 11, and the prongs of the fasteners bent back to engage flap 26c. By such an arrangement the bent-over prongs are covered by the front and back sheets 15, 21, respectively.

Referring now to the embodiment illustrated in Figs. 7, 8 and 9 of the drawings, Fig. 7 is illustrative of a blank from which the binding cover and envelope illustrated in Figs. 8 and 9 may be formed. Such a blank is cut and formed to provide a back sheet 40 defined by lines of fold 41, 42, 43, 44, and a front sheet 45 defined by the left hand marginal edge 46, the line of fold 41, the bottom marginal edge 47, and a top line of fold 48.

Extending upwardly of the back sheet 40 is a flap 50, and extending upwardly from the front sheet 45 is a flap 51, both said flaps corresponding to the flaps 25, 26 of the Fig. 4 blank.

The back sheet 40 is provided with a flap 52 adapted to fold forwardly of the back sheet along line of fold 42 and serves to protect and reinforce said sheet along this line of fold.

Carried by the back sheet 40 and adapted to fold upwardly relative thereto along the line of fold 44 is a pocket-forming flap 54, said flap extending the full width of the back sheet and being defined laterally by lines of fold 55, 56 which are, respectively, continuations of the lines of fold 41, 42. The pocket-forming flap 54 is provided at each side thereof with securing flaps 58, 60 each adapted to fold relatively forwardly of the flap 54 along the lines of fold 55, 56. As will be seen from the drawings, flaps 58, 60 extend substantially the full depth of flap 54.

In setting up a binding cover and envelope from the blank illustrated in Fig. 7, the front sheet 45 is folded over the back sheet 40 along the line of fold 41. Longitudinal side flap 52 may now be folded inwardly of the back sheet 40 along line

of fold 42, to take up a position intermediate the front and back sheets 45, 40, respectively. Bottom flap 54 may now be folded relatively upwardly along line of fold 44 to overlie the front sheet 45 in the manner indicated in Figs. 8 and 9, 5 whereupon wing flaps 58, 60 are bent relatively rearwardly along lines of folds 55, 56. Flap 58 is adapted to engage against the rear face of the back sheet 40 and is glued to the latter. On the other hand, the right hand flap 60 is folded over edge 46 of the front sheet, being positioned between said sheet and the back sheet in the manner indicated in Fig. 9. Said flap 60 is thereupon glued to the rear face of the front sheet 45. Flaps 50, 51 may now be bent forwardly along 10 the related lines of fold 43, 48. Said flaps are preferably unglued and the sheets 11 to be bound are secured therebetween in the manner indicated in Fig. 2. If glued together, the binding corresponds to that illustrated in Fig. 3. 20

In such a construction as last above described, the lower edges of the bound sheets may be projected into the pocket formed adjacent the bottom of the binding cover by the described relationship of flap 54 and front sheet 45 thereof. As with the 25 previously described constructions, the cover under description is provided by front and back sheets which are secured together along their top, bottom and one side edges, being unsecured along their other edge such as their right edge. 30 Accordingly an open-sided envelope construction is provided which is adapted to receive and store drawings, correspondence, data and the like which pertain to the subject-matter of the sheets bound by the binding flaps. 35

The cover and envelope illustrated in Fig. 11, a part-blank for which is illustrated in Fig. 10, embodies the same general principles employed in the cover and envelope illustrated in Figs. 7-9. In the latter embodiment, however, securing flaps 40 such as the flaps 58, 60 are dispensed with, and the pocket securing flap 54a is defined laterally by the marginal edges 55a, 56a. In setting up the binding cover and envelope from the blank illustrated in Fig. 10, the same operations are practiced as in setting up a structure from the Fig. 7 blank up to the point of bending and securing flaps 58, 60. From this point, flap 54a is secured along its left marginal edge 55a to the back face of the back sheet 40a as by a strip of gummed 50 fabric 62 as indicated in Figs. 11 and 12. Similarly, flap 54a along its right marginal edge 56a is secured to the front sheet 45a and to the under face thereof by a similar strip of gummed fabric 63. Upon securement being effected as aforesaid, a 55 pocket adapted to receive the lower ends of the bound sheets is provided between the relatively inner face of flap 54a and the relatively front face of the front sheet 45a.

Preferably, the blanks above described from 60 which the combined binding cover and envelope is fabricated as aforesaid are cut from a fabric material, thus to provide a cover and envelope of relatively long life under hard conditions of usage. It will be understood, however, that materials 65 other than fabric may be employed, such as heavy paper of the character employed in conventional bindings.

It is further to be understood that minor changes may be made in the above described constructions without departing from the scope of this invention. For example, the flaps 32 and 52 may be omitted entirely. On the other hand, a flap analogous to the flap 52 may be provided along the marginal edge 22 of the back sheet (Fig. 7)

40, thus to protect this raw edge of the envelope mouth. Similarly a flap such as the flap 32 may be provided along the marginal edge 46 of the blank illustrated in Fig. 7, thus to protect and 5 reinforce this raw or cut edge of the envelope mouth.

Hence, as the above and other changes could be made in carrying out the above constructions without departing from the scope of the invention, 10 it is intended that all matter contained in the above description or shown in the accompanying drawings shall be interpreted as illustrative and not in a limiting sense.

I claim:

15 1. A binding cover and envelope construction fabricated from a blank cut and folded to form front and back cover sheets secured together along a common line of fold which constitutes one side edge of the construction, means securing said 20 cover sheets together along their bottom edges, a binding flap extending from the top edge of each of said cover sheets, said flaps being folded to overlie the front sheet along a line of fold constituting the top edge of the construction, means 25 adapted to secure a plurality of sheets to be bound to said binding flaps and functioning also to secure the flaps together, said cover sheets having cooperating means forming with said front sheet an upwardly opening pocket adapted 30 to receive the lower portions of the bound sheets, the front and back cover sheets being unsecured along their other side edges whereby said sheets form an open-sided envelope.

2. A binding cover and envelope construction 35 fabricated from a blank cut and folded to form front and back cover sheets secured together along a common line of fold which constitutes one side edge of the construction, one of said cover sheets carrying means for securing said 40 sheets together along their related bottom edges, a binding flap extending from the top edge of each of said cover sheets, said flaps being folded to overlie the front sheet along a line of fold constituting the top edge of the construction, means 45 adapted to secure a plurality of sheets to be bound to said binding flaps and functioning also to secure the flaps together, said cover sheets having cooperating means forming with said front sheet an upwardly opening pocket adapted 50 to receive the lower portions of the bound sheets, the front and back cover sheets being unsecured along their other side edges whereby said sheets form an open-sided envelope.

3. A binding cover and envelope construction 55 fabricated from a blank cut and folded to form front and back cover sheets secured together along a common line of fold which constitutes one side edge of the construction, one of said cover sheets carrying means for securing said 60 sheets together along their related bottom edges, a binding flap of substantially uniform depth and of width approximating that of the sheets extending from the top edge of each cover sheet, said flaps being folded to overlie the front cover 65 sheet along a line of fold constituting the top edge of said construction, means adapted to secure a plurality of sheets to be bound to said flaps and functioning also to secure the flaps together, said cover sheets having cooperating 70 means forming with said front cover sheet an upwardly opening pocket adapted to receive the lower portions of the bound sheets, the front and back cover sheets being unsecured along their other side edges whereby said sheets form an 75 open-sided envelope.

4. A binding cover and envelope construction fabricated from a blank cut and folded to form front and back cover sheets secured together along a common line of fold which constitutes one side edge of the construction, one of said 5 cover sheets carrying means for securing said sheets together along their related bottom edges, a binding flap extending from the top edge of each of said cover sheets, said flaps being folded to overlie the front sheet along a line of fold 10 constituting the top edge of the construction, the binding flap of one sheet being of substantially greater depth than the binding flap of the other sheet and being folded on itself, the binding flap of said other sheet being interleaved with 15 said first flap, means adapted to secure a plurality of sheets to be found to said binding flaps, said front and back sheets having cooperating means forming with said front sheet an upwardly opening pocket adapted to receive the lower 20 portions of the bound sheets, the front and back cover sheets being unsecured along their other side edges, whereby said sheets form an open-sided envelope.

5. A binding cover and envelope construction 25 fabricated from a blank cut and folded to form front and back cover sheets secured together along a common line of fold which constitutes one side edge of the construction, one of said 30 cover sheets carrying means for securing said sheets together along their related bottom edges, a binding flap extending from the top edge of each of said cover sheets, said flaps being folded to overlie the front sheet along a line of fold constituting the top edge of the construction, the binding flap of one cover sheet being bent on 35 itself to form a plurality of binding plies, the binding flap of the other cover sheet constituting a single ply adapted to be interleaved with the multi-ply flap, means adapted to secure a plurality of sheets to be bound to said binding flaps, said cover sheets having cooperating means forming with the front sheet an upwardly opening 40 pocket adapted to receive the lower portions of the bound sheets, the front and back cover 45 sheets being unsecured along their other side edges whereby said sheets form an open-sided envelope.

6. A binding cover and envelope construction 50 fabricated from a blank cut and folded to form front and back cover sheets secured together along a common line of fold which constitutes one side edge of the construction, one of said 55 cover sheets carrying means for securing said sheets together along their related bottom edges, a multi-ply binding flap extending from the top 60 edge of the back sheet, a single-ply flap extending from the top edge of the front sheet, said flaps being folded to overlie the front sheet along a line of fold constituting the top edge of the construction, the single-ply flap being interleaved with the plies of the multi-ply flap, means 65 for securing a plurality of sheets to be bound to said binding flaps, said cover sheets having cooperating means forming with the front sheet an upwardly opening 70 pocket adapted to receive the lower portions of the bound sheets, the front and back cover sheets being unsecured along their other side edges whereby said sheets form an open-sided envelope.

7. A binding cover and envelope construction 75 fabricated from a blank cut and folded to form front and back cover sheets secured together along a common line of fold constituting one side edge of the construction, a binding flap extend-

ing upwardly from each cover sheet and being folded along a line of fold constituting the top edge of said construction to overlie the front cover sheet, means for securing the sheets to be 5 bound to said binding flaps, one of said cover sheets having a flap extending the full width thereof from its bottom edge, said flap being folded along a line of fold constituting the bottom edge of said construction into facing relation with said other cover sheet and being secured to said other cover sheet whereby to secure said cover sheets together along their related bottom edges, said cover sheets being unsecured along their other side edges whereby said 10 sheets form an open-sided envelope.

8. A binding cover and envelope construction fabricated from a blank cut and folded to form front and back cover sheets secured together along a common line of fold constituting one side edge of the construction, a binding flap extending upwardly from each cover sheet and being folded along a line of fold constituting the top edge of said construction to overlie the front cover sheet, means for securing the sheets to be bound to said binding flaps, the back sheet having a flap extending the full width thereof from its bottom edge and folded to overlie the front sheet along a line of fold constituting the bottom edge of said construction, means securing the bottom flap along its side edges to the cover sheets, whereby to secure the cover sheets together along their bottom edges and whereby said bottom flap forms with the front cover sheet an upwardly opening pocket adapted to receive the bottom ends of the bound sheets, the front and back cover sheets being unsecured along their other side edges whereby said sheets form an open-sided envelope.

9. A binding cover and envelope construction fabricated from a blank cut and folded to form front and back cover sheets secured together along a common line of fold constituting one side edge of the construction, a binding flap extending upwardly from each cover sheet and being folded along a line of fold constituting the top edge of said construction to overlie the front cover sheet, means for securing the sheets to be bound to said binding flaps, said front cover sheet having a flap extending the full width thereof from its bottom edge, said flap being folded to underlie the back cover sheet along a line of fold constituting the bottom edge of the construction and being secured to the rear face of the back sheet thereby to secure said cover sheets together along their related bottom edges, the front cover sheet having a transverse slit extending substantially the width thereof, said slit being spaced from said bottom edge and forming the mouth of a pocket provided by said front and back cover sheets along the aforesaid bottom edge, said pocket being adapted to receive the bottom ends of the bound sheets, the front and back cover sheets being unsecured along their other side edge whereby said sheets form an open-sided envelope.

10. A binding cover and envelope construction fabricated from a blank cut and folded to form front and back cover sheets secured together along a common line of fold constituting one side edge of the construction, a binding flap extending upwardly from each cover sheet and being folded along a line of fold constituting the top edge of said construction to overlie the front cover sheet, means for securing the sheets to be bound to said binding flaps, said front cover sheet having a flap extending the full width thereof from its bottom edge, said bottom flap having a wing flap extending laterally therefrom which is folded over

the closed side edge of the construction to overlie the front cover sheet, said bottom flap being secured to the rear face of the back sheet and said wing flap being secured to the front face of the front sheet thereby to secure said cover sheets 5 together along their related bottom edges, the front sheet having a transverse slit extending substantially the width thereof, said slit being spaced from said bottom edge and providing an upwardly opening mouth for a pocket formed by 10 said front and back sheets above the aforesaid bottom edge, the cover sheets being unsecured along their other side edges whereby said sheets form an open-sided envelope.

11. A binding cover and envelope construction 15 fabricated from a blank cut and folded to form front and back cover sheets secured together along a common line of fold constituting one side edge of the construction, a binding flap extending upwardly from each cover sheet and being 20 folded along a line of fold constituting the top edge of said construction to overlie the front cover sheet, means for securing the sheets to be bound to said binding flaps, the back sheet having a flap extending the full width thereof from 25 its bottom edge and folded to overlie the front sheet along a line of fold constituting the bottom edge of said construction, means securing the bottom flap along its side edges to the cover sheets, whereby to secure the cover sheets together along their bottom edges and whereby said bottom flap forms with the front cover sheet an upwardly opening pocket adapted to receive the bottom ends of the bound sheets, the front and back cover sheets being unsecured along 30 their other side edges whereby said sheets form an open-sided envelope.

12. A binding cover and envelope construction fabricated from a blank cut and folded to form front and back cover sheets secured together 40 along a common line of fold constituting one side edge of the construction, a binding flap extending upwardly from each cover sheet and being folded along a line of fold constituting the top edge of said construction to overlie the front cover sheet, means for securing the sheets to be bound to said binding flaps, the back sheet having a flap extending the full width thereof from 45 its bottom edge and folded to overlie the front sheet along a line of fold constituting the bottom edge of said construction, means securing the bottom flap along one side edge corresponding to the closed side edge of the construction to the rear face of the back cover sheet and along its other side edge to the rear face of the front cover sheet, whereby to secure the cover sheets together along their related bottom edges and whereby said bottom flap forms with the front cover sheet an upwardly opening pocket adapted to receive the bottom ends of the bound sheets, the front and back cover sheets being unsecured along their other side edges whereby said sheets form an 50 open-sided envelope.

13. A binding cover and envelope construction 65 fabricated from a blank cut and folded to form front and back cover sheets secured together along a common line of fold constituting one side edge of the construction, a binding flap extending upwardly from each cover sheet and being folded along a line of fold constituting the top edge 70 of said construction to overlie the front cover sheet, means for securing the sheets to be bound to said binding flaps, the back sheet having a flap extending the full width thereof from its bottom edge and folded to overlie the front sheet 75

- along a line of fold constituting the bottom edge of said construction, a wing flap extending from the bottom flap at each side thereof, one wing flap being folded over the closed side edge of 5 the construction and being secured to the rear face of the back sheet and the other wing flap being folded over the free edge of the front sheet and being secured to the rear face of the latter, thereby to secure the cover sheets together along 10 their bottom edges and whereby said flap forms with the front cover sheet an upwardly opening pocket adapted to receive the bottom ends of the bound sheets, the front and back cover sheets being unsecured along their other side edges 15 whereby said sheets form an open-sided envelope.
14. A binding cover and envelope construction fabricated from a blank cut and folded to form front and back cover sheets secured together along a common line of fold constituting one side 20 edge of the construction, a binding flap extending

upwardly from each cover sheet and being folded along a line of fold constituting the top edge of said construction to overlie the front cover sheet, means for securing the sheets to be bound to said binding flaps, the back sheet having a 5 flap extending the full width thereof from its bottom edge and folded to overlie the front sheet along a line of fold constituting the bottom edge of said construction, a securing strip for securing one side edge of the flap to the under face of the 10 back cover sheet, a securing strip for securing the other side edge of the bottom flap to the under face of the front cover sheet, said securing strips operating to secure the cover sheets together along their bottom edges and to secure the 15 bottom flap in pocket-forming relation with the front cover sheet, the front and back cover sheets being unsecured along their other side edges whereby said sheets form an open-sided envelope.

GLENN SWIFT. 20
